UNITED STATES PATENT OFFICE

ALANSON T. S. YATES, OF DULUTH, MINNESOTA

DENTAL LIGATURE APPLICATOR

Application filed January 10, 1929. Serial No. 331,487.

My invention relates to instruments for use in maintaining sanitary conditions of the human mouth and has special reference to a device for applying a ligature intermediate 5 of the teeth for cleansing same; the principal object being to provide a more convenient and practical instrumentality than heretofore known for such purpose.

Another object is to provide a novel form 10 of ligature especially adapted for such purpose.

Other objects and advantages of the invention will appear in the further description thereof.

15 Referring now to the accompanying drawings, forming part of this application, and wherein like reference characters indicate like parts:

Figure 1 is a side elevation of one embodiment of my improved applicator with the ligature omitted therefrom;

Figure 2 is a front end elevation of the applicator with the ligature applied;

Figure 3 is a top plan view of the applicator with the ligature omitted; and

Figure 4 is a plan view, opposite to that shown in Figure 3, with the ligature applied.

In the embodiment here illustrated, particularly in Figure 1, I have shown my improved form of applicator as being in conjunction with the handle of a common tooth brush, this being a preferred type of the instrument, and resides specifically in forming the free end of the handle portion 1 of the brush with a right angularly disposed U-shaped extension 2, the prongs of which are preferably somewhat arcuate in shape as viewed from the front elevation thereof and with their termini spaced a distance apart for readily straddling the space intermediate of the teeth in the average human mouth. The inner edges of the prongs I prefer to form of protruding V-shape as at 3 with the apexes thereof directly opposed so as to readily fit intermediate of the teeth without necessarily engaging same.

About each circumferential face of the prongs and in the uppermost termini thereof is formed a V-shaped channel 4 for the reception of the ligature 5 which I prefer to be of

and consider as novel a small rubber elastic band.

Upon the under side and back of the handle of the instrument and just inwardly of the termini of the V-shaped channels 4 is formed a small button or knob 6, either integral with the handle, which is usually composed of a composition such as celluloid or the like, or attached thereto. Spaced therefrom inwardly upon the handle and preferably adjacent the opposite end is a like button or knob 7 so that when placing the ligature or rubber band transverse the prongs of the instrument and about same the band may be brought around on opposite sides of the knob or button 6, and thence drawn taut to and about the button 7, when the instrument is ready for use and the band thus held firmly for the purpose desired.

While I have shown the instrument as forming a part of the handle of a tooth brush, it is apparent that it may be independently of same, and function equally as well, and that the ligature employed may be any of the well known brands in lieu of the rubber elastic above described.

Having thus described my invention, what I claim and desire to secure by Letters Patent, is:

An instrument of the class described comprising a handle, a U-shaped extension on and at right angles to one end of said handle, channels about the sides and termini of the extension, a button at the base of the extension, a second button spaced inwardly of the first mentioned button, and a ligature of endless rubber within the channels and about the buttons.

In testimony whereof I affix my signature.

ALANSON T. S. YATES.
